UNITED STATES PATENT OFFICE.

HARRY SUSSMAN, OF BROOKLYN, AND RAFAEL SCHNELL, OF NEW YORK, N. Y.

DESIGN FOR A CANDLESTICK.

Application filed September 11, 1924. Serial No. 10,733. Term of patent 3½ years.

To all whom it may concern:

Be it known that we, HARRY SUSSMAN and RAFAEL SCHNELL, citizens, respectively, of Austria and of the United States of America, and residents, respectively, of the city of New York, borough of Brooklyn, in the county of Kings and State of New York, and of the city of New York, borough of Manhattan, in the county and State of New York, have invented a new, original, and ornamental Design for Candlestick, of which the following is a specification.

Reference is had to the accompanying drawing in which the figure is a view in elevation of a candlestick showing our new design.

We claim:

The ornamental design for a candlestick as shown.

HARRY SUSSMAN.
RAFAEL SCHNELL.
